BATHROOM CERAMIC WASH BASIN OR SIMILAR ARTICLE

Antonia Campi, Laveno Mombello, Italy, assignor to Società Ceramica Italiana Richard-Ginori Società per Azioni, Milan, Italy

Filed Oct. 7, 1966, Ser. No. 4,200

Claims priority, application Italy Apr. 7, 1966

Term of patent 14 years

(Cl. D4—2)

FIG. 1

FIGURE 1 is a front perspective view of a bathroom ceramic wash basin or similar article showing my new design;

The dominant features of my design reside in the portions shown in full lines.

I claim:

The ornamental design for bathroom ceramic wash basin or similar article, as shown and described.
